UNITED STATES PATENT OFFICE

2,542,362

SUPPLY OF FUEL TO THE CARBURETORS
OF AUTOMOBILESLeslie James Ryan, East Malvern, Victoria,
AustraliaApplication December 16, 1947, Serial No. 791,965
In Australia April 2, 1947

2 Claims. (Cl. 123—119)

1

This invention relates to the feeding of fuel from the fuel tank of an automobile to the carburettor or similar device for converting the fuel into an explosive gaseous mixture.

For that purpose, it is the usual practice to fit an electric or mechanically operated pump in a pipe line extending from the fuel tank to the inlet of a carburettor or the like. It has long been realised that such fuel pumps are a source of trouble and this is particularly the case with automobiles having a low centre of gravity or in which the fuel pump and the pipe leading thereto to the carburettor, especially the latter, are in relatively close proximity to the engine of the vehicle. The heat developed by the latter during operation tends to create vapour in the pumping system which gives rise to vapour locks and other disadvantages liable to interfere with continuous and efficient operation of the pump.

Trouble is often experienced by reason of the suction valves of the pumps becoming inefficient through wear or through blockage caused by foreign particles being drawn up in the fuel from the supply tank. Thus, air-leaks at the suction side of a pump will very often cause the pump to break down owing to the low suction effect which is usually equivalent to about 5 to 10 inches of vacuum.

The present invention aims to overcome the beforementioned and other such disabilities, and for this purpose it contemplates a booster device which is connected between the delivery side of the fuel pump and the induction manifold so that the relatively high suction effect obtaining in the latter and ranging from, say, 10 to 21 inches of vacuum may be utilized to correct or overcome any mal-operation of the fuel pump and ensure a substantially continuous delivery of fuel to the carburettor or other suction device.

The invention is illustrated in the accompanying drawings, in which:

Figure 1 is a sectional elevation of a booster device according to one form of the invention.

Figure 2 is a general lay-out of a typical booster installation according to the invention.

Figure 3 illustrates one way in which the invention may be applied to a well known make of automobile.

Figure 4 is a sectional elevation of a control device seen in Figures 2 and 3.

Figure 5 shows an alternative way of connecting the booster to a carburettor.

The booster device, as best seen in Figure 1, comprises a casing 2, preferably cylindrical, relatively small but longitudinally elongated and

2

arranged in a vertical, or substantially vertical, attitude. The interior of the chamber provides a chamber 3 having restricted communication at its bottom with a passage 4 adapted to communicate respectively with a fuel pump 6 and a carburettor or like device 7 (Figures 2 and 3).

A float 8, which may be of cork or in the form of a brass or other thin-walled cylinder, is loosely disposed within the casing so that it will rise and fall according to variations in the level of liquid fuel entering the chamber. The upper end of the float may have a part spherical recess 8a to accommodate a steel or other suitable ball 9 which is capable of sealing a ball-seat 11 formed in the lower end of a hollow cap 12 affixed to the upper end of the casing. The vertical passage 12a of the cap may be connected by a pipe 13 (indicated by unbroken lines in Figure 2) leading to a suitable position in the fuel inlet manifold 14 of the engine 15.

With such a device operatively installed, the suction effect from the fuel inlet manifold 14 propagates through the fuel pump 6 and causes the fuel to be induced into the carburettor 7. At the same time, some of the fuel rises into the chamber 3 of the booster device so that the float 8 ascends, thereby bringing the ball-valve 6 towards its seating 11 against which it is eventually held by the suction from the manifold 14, thus cutting off communication between the booster and the inlet manifold.

In the event of the pump 6 failing to operate or operating with materially decreased efficiency, the float 8 descends and the ball-valve 6 falls from its seating 11 into the recess at the upper end of the float 8, thus allowing the suction effect from the manifold 14 to propagate through chamber 3 to the fuel pump 6 and to draw fuel through the pump and thence to the carburettor. A similar action takes place in the event of a vapour lock occurring in the pump.

Experiments carried out with the device as before described show that it is possible to start a cold engine quickly even with an old or defective fuel pump for the reason that the booster device provides for a relatively high degree of suction being created immediately the starter-motor is operated and provides for a practically instantaneous supply of fuel to the carburettor.

As it may not always be desirable for the booster to be in operation, I contemplate inserting in the pipe 13 which leads from the top of the booster casing 2 to the fuel inlet manifold, a suitable control which may be operated from the driver's seat. This control as best seen in

Figure 4 may take the form of a valve casing 16 retained by a screw 17 and nut 18 to the dash board or instrument panel 19 and having ports 21, 22 with which the respective ends of sections 13a, 13b, of pipe 13 register. The control member may advantageously consist of a valve stem 23 adjustable lengthwise within the bore of casing 16 by co-operation of a screwed portion 23a of the stem with a screw threaded entry of the casing, the outer end of the stem having a knarled head 23b. It will be apparent that, by moving the valve stem inwardly from the open position indicated in Figure 2, communication between the top of the booster chamber 3 and the intake manifold 14 will be cut-off and the booster device rendered inoperative.

A further refinement involves the interposition of a non-return valve between the fuel inlet of the carburettor 7 and the carburettor side of the through-passage 4 communicating with the lower part of the booster chamber 3. This is best seen in Figure 1 where it is assumed that a hollow T piece 26 screwed on to the lower end of casing 2 has the through-passage 4 formed therein and has a screwed nipple 27 at one side for connection to the fuel pump 6 and an enlarged bore 28 at the other side which is internally screw threaded to receive a screw threaded sleeve 29. The latter provides an annular abutment face 30 for one end of a compression spring 31 which bears at its other end against a valve disc or washer 32 and tends to force the latter against the annular valve seating 33 created between one end of through-passage 4 and the adjacent end of the enlarged bore 28. Thus, when the booster is operating and the suction effect propagates from the intake manifold 14 through the booster to the through-passage 4, the valve 32 will be held against its seating and ensures that the entire suction effect will be directed to the fuel pump. Then, after the necessary pressure has been built up by the fuel pump, the valve 32 will be automatically forced open to permit the fuel to be delivered to the carburettor. Of course, this would not apply if the carburettor is fully charged with fuel, as the usual needle valve would offer sufficient restriction to further delivery of fuel, but if the carburettor were empty, the valve would remain closed and prevent the suction effect from being dissipated through the empty carburettor.

In Figure 3, the booster device is shown applied to a well known "V eight" automobile engine, and wherein the nipple 27 is applied directly to the delivery side of the fuel pump 6 while a pipe 34 leads from the enlarged-bore end of T piece 26 to the inlet of the carburettor 7.

According to Figure 5, the enlarged-bore end of T piece 26 is connected directly to the inlet of the carburettor 7 while the nipple 27 is connected by a pipe 36 to the delivery side of the fuel pump.

Having now described my invention, what I

claim as new and desire to secure by Letters Patent is:

5 1. A booster device for association with a fuel pump for supplying fuel to the carburettor of an automobile engine having a fuel intake manifold, comprising a casing having at its bottom a hollow part providing a through-passage for providing communication between the delivery side of the fuel pump and the fuel inlet side of the carburettor, the interior of the casing constituting a float chamber communicating exclusively at its bottom with the upper portion of said through-passage, a float in said chamber, a hollow member closing the upper part of said casing and having a valve seat facing the top of the said float, said hollow member having a passage extending upwardly from said valve seat for communication with said fuel intake manifold, and a valve member including a ball unattached to said float but capable of resting upon the upper surface thereof so that the ball may, by rising of the float or by being drawn upwards from the top of the float by suction, be forced against said seat to cut off communication between the float chamber and the fuel intake manifold.

20 2. A booster device for association with a fuel pump for supplying fuel to the carburettor of an automobile engine having a fuel intake manifold, comprising a casing having at its bottom a hollow part providing a through-passage for providing communication between the delivery side of the fuel pump and the fuel inlet side of the carburettor, the interior of the casing constituting a float chamber communicating exclusively at its bottom with the upper portion of said through-passage, a float in said chamber, having a recess in the upper surface thereof, a hollow member closing the upper part of said casing and having a valve seat facing the top of said float, said hollow member having a passage extending upwardly from said valve seat for communication with said fuel intake manifold, and a valve member including a ball unattached to said float but capable of resting in the recess in the upper surface thereof so that the ball may, by rising of the float or by being drawn upwards from the top of the float by suction, be forced against said seat to cut off communication between the float chamber and the fuel intake manifold.
